UNITED STATES PATENT OFFICE.

NILS P. SEABERG, OF BOSTON, MASSACHUSETTS.

PICTURE-FRAME CONSTRUCTION.

1,053,114.

Specification of Letters Patent. Patented Feb. 11, 1913.

Application filed December 5, 1910. Serial No. 595,640.

To all whom it may concern:

Be it known that I, NILS P. SEABERG, a citizen of the United States, residing at Boston, in the county of Suffolk and State 5 of Massachusetts, have invented new and useful Improvements in Picture-Frame Constructions, of which the following is a specification.

This invention relates to picture frames.

10 More particularly it relates to the construction of frames formed of sheet metal with removable back and adapted to permit of the easy insertion and removal of the picture.

15 The objects of the invention are to provide a frame of the character indicated in which the construction of frame is simple and inexpensive, and of the particular character hereinafter described, and yet is firm 20 and finished notwithstanding its separability at two of the corners; and in which also the back and entire frame are held latched when in normal position.

One embodiment of the invention by 25 which these objects are accomplished is shown in the accompanying drawings, in which—

Figure 1 is a front elevation of a frame embodying the invention, showing also in 30 dotted lines the position of one side and the back when partly removed; Fig. 2 is an elevation of the rear, the side and back being shown in full lines in the position in which they are dotted in Fig. 1; Fig. 3 is 35 a bottom view partly in section as indicated by the line 3—3 of Fig. 2; Fig. 4 is an end elevation in section on the line 4—4 of Fig. 2; Fig. 5 is an end view of a detail on a larger scale, representing a section at 40 the position 5—5 of Fig. 3 when the back, unlike Fig. 3, is closed; and Fig. 6 is a view on the larger scale of a detail seen at the right in Fig. 3, with the parts in a different position.

45 Referring to the drawings, 10 indicates the back of the frame, the end and side pieces or bars constituting the frame being marked 11, 12, 13 and 14. In the structure illustrated the frame is formed of sheet 50 metal formed U-shaped or channel-form in cross-section. The back is of sheet metal. The edges of the back, the picture and the glass fit into channels so that the two side members 11 and 13, and the end member 12 55 surround and bind them together. The channels are a little wider than necessary

to receive the parts named, partly to provide for varying thicknesses of glass or cardboard and partly to provide for the spring action of the back hereinafter described. The fourth part of the frame 14, 60 is integral with or fixedly attached to the back 10, surrounds the fourth edge of the glass and picture, and serves as a handle by which the back may be withdrawn, by 65 sliding edgewise through the channels in 11 and 13. The sides 11, 12 and 13 of the frame are integral with each other, or are in some way permanently fixed together. It will be observed that by this construction 70 the members 11 and 13 are attached to each other only by the member 12, which is at one extremity; and that their ends toward the member 14 are free and without any immediate support when member 14 is withdrawn; and that at that time the space 75 between them is wholly unobstructed.

The face of the frame may be finished in any desired pattern, but at the corners where the member 14 joins the members 11 and 13, 80 the line of separation may conveniently be, and is hereby represented as being, a diagonal line, the same being marked 15, corresponding to the similar diagonal lines 15' 85 seen at the corners formed at the ends of the member 12. These are formed easily and naturally by the coming together of the sides of the channel-form, suitable portions being excised from the sides of the channel-form before the bending occurs. Thus a 90 symmetrical face is obtained which gives no indication of the separability and in which the separable and the inseparable corners 95 look alike. That portion of the member 14 which forms the middle of its channel is 100 cut somewhat longer than the sides of the channel and the projections thus constituted are at each end bent at right angles into parallelism with the members 11 and 13, forming two ears 16 which are set at proper 105 distances apart so that they embrace or engage externally the ends of the members 11 and 13. For a more perfect finish slight depressions 17, may be formed in the ends of members 11 and 13 as illustrated, into which 110 the ears 16 fit so that they lie flush with the main surfaces of the members 11 and 13, and normally are not noticeable. They however, serve the important and novel function of holding rigidly in position these two ends, 110 of 11 and 13, which otherwise are ill-supported, these members being held only at

the far remote ends by the bar 12. This keeps these free ends from spreading. They are kept from collapsing by the side portions of their channel-form contacting with 5 the side portions of the channel-form member 14, at the places marked 15. Thus the end member carries means by which the ends of members 11 and 13 are spaced properly and held rigidly against either excessive 10 spreading or excessive approach to each other; and are held against twisting because the sides of the channel have a bearing with the sides of the channel in the member 14 on both sides of its channel.

15 The back 10, is preferably formed of spring metal and is somewhat dished in shape, its center passing toward the face of the frame and its edges toward the back. Its edge remote from the member 14 is preferably turned outward and backward so that it forms an upstanding lip 20. The back 20 side of the channel of member 12 is bent suitably opposite that lip so that it forms a ledge or catch 21 in which the lip may engage when pushed inward, the elasticity of 25 the back throwing the lip into engagement. The parts are so designed that this engagement occurs only when the back has been pushed to such a position that the ears 16 and the face joints 15 are properly seated. In consequence of this construction the 30 back may be removed at any time by the user pressing lightly upon the inner end of the back to disengage the lip 20, and at the same 35 time pulling upon the member 14, whereby the bar 14 of the frame and the back are drawn out, leaving the photograph or other contents of the frame to be readily removed or inserted with great convenience, 40 and without danger of damage by rubbing along the face of the glass, a danger which exists in many types of apparatus intended for this purpose as heretofore known. The 45 frame at the ends of members 11 and 13 re- mote from member 12 contributes to this

result by separating, as these members easily swing or bend open a little at the corners 15'. The back may be inserted with equal ease. The picture having been put in position, the only friction or rubbing which 50 occurs is on the back of the cardboard. At the instant when the back is pressed home, the free ends of members 11 and 13 become locked rigidly in proper position, and the lip 20 is snapped into its engaged position. The frame remains thus stiff and firm without danger of separation.

55 I claim as my invention:—

1. The combination of a frame for pictures or the like, comprising bars having 60 channels opening internally and adapted to receive the edges of the contents of the frame, combined with a plate having edges adapted to occupy said channels with the contents, forming a back for the frame; the 65 frame having a removable side to which said back is attached, sliding edgewise through the channels in the sides of the frame adjacent to said removable side; there being a formation of the side of the channel 70 in that part of the frame opposite the removable side to constitute one member of a latch, and a formation in the end of the back to constitute the other member of the latch, for holding the parts in place. 75

2. The combination, in a frame for pictures or the like, of a removable connected side and back of the frame, the back being adapted to slide in channels in other sides of the frame; the first mentioned side, 80 when the frame is closed embracing the free ends of the other sides; and latch means to hold such embracement.

Signed by me at Boston, Mass., this 26th day of November, 1910.

NILS P. SEABERG.
